CLAIM

The ornamental design for a display assembly for golf equipment, as shown and described.

DESCRIPTION

FIG. 1 is a front elevation view of the display assembly for golf equipment showing a new design, with part of the golf club only shown in broken lines for environmental purposes; FIG. 2 is a plan view thereof, with broken lines in the card shown for illustrative purposes;

FIG. 3 is a partial exploded view thereof, with broken lines in the club only shown for environmental purposes; and, FIG. 4 is a side elevation view thereof, with broken lines in the club only shown for environmental purposes.

The use of broken lines in FIGS. 1-4 does not form any part of the claimed design.
